Primary Examiner — Abraham Bahta(74) *Attorney, Agent, or Firm* — Daniel J. Layden; Brandon J. Lee(57) **CLAIM**

The ornamental design for a “reclosable shopping bag,” as shown and described.

DESCRIPTION

FIG. 1 is a front perspective view of a reclosable shopping bag embodying my new design;

FIG. 2 is a front plan view thereof;

FIG. 3 is a rear plan view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings are for illustrative purposes only and do not form a part of the claimed design. The stippling in the drawings disclose a contrasting surface.
